UNITED STATES PATENT OFFICE.

NEIL McINNES, OF ALLEGHENY, PENNSYLVANIA.

PRESSED-STEEL CONNECTING-BAR.

No. 840,237.

Specification of Letters Patent.

Patented Jan. 1, 1907.

Application filed October 12, 1906. Serial No. 338,576.

To all whom it may concern:

Be it known that I, NEIL McINNES, a citizen of the United States of America, residing at Allegheny, in the county of Allegheny and State of Pennsylvania, have invented certain new and useful Improvements in Pressed-Steel Connecting-Bars, of which the following is a specification, reference being had therein to the accompanying drawings.

10 This invention relates to pressed-steel connecting-bars adapted for use as car-truck levers, connections for the switch-points of railway-switches, and for other purposes.

The primary object of the invention is to 15 provide a pressed-steel connection of light but strong and durable construction capable of being manufactured at small expense of labor and material.

The construction of the improvement will 20 be fully described hereinafter in connection with the accompanying drawings, which form a part of this specification, and its novel features will be defined in the appended claims.

25 In the drawings, Figure 1 is a top plan view of a blank from which the improved connection is made. Fig. 2 is a side elevation of a connection constructed in accordance with the invention. Fig. 3 is a top plan view of the same. Fig. 4 is an end view thereof. Fig. 5 is a transverse section on the line $x-x$ of Fig. 2, and Fig. 6 is a similar section illustrating a modified construction.

The reference-numeral 1 designates a 30 blank comprising a flat steel plate, longitudinally slotted and perforated at its ends to provide parallel arms 2, rounded at their outer extremities 3. The blank as thus formed is then pressed at one operation to the form 35 shown in Figs. 2 to 5, inclusive. The body form in cross-section and is deflected upward portion 4 of the blank is bent to inverted-U at the points 5, and the arms 2 are brought 40 into vertical parallel relation with the openings 6 of each pair of arms registering, as shown. This pressing of the blank provides a body portion of great strength and rigidity and projects the ends and perforated arms upward to facilitate their attachment to the 45 elements to which they are to be secured.

The construction of the complete device requires only two operations—viz., the stamping out of the blank and the pressing of the same to completed form.

In Fig. 6 I have shown a transverse section of a slightly-modified construction, in which the side walls 7 after being pressed into the parallel relation shown in Fig. 5 are pressed inward toward each other, which form may be preferred for certain purposes. 55 This modification will involve an additional step or operation in the process of manufacture; but such further operation will add to the compactness and finished appearance of the connection.

What I claim, and desire to secure by Letters Patent, is—

1. A pressed-steel connection comprising a blank formed at its ends with longitudinal slots and having its body portion pressed to 70 inverted-U shape in cross-section.

2. A pressed-steel connection comprising a flat blank longitudinally slotted and perforated at its ends, and pressed to provide a body portion of inverted-U shape in cross-section, and parallel upwardly-directed arms. 75

3. A pressed-steel connection comprising a body portion of inverted-U shape in cross-section having its ends upwardly inclined, and provided with parallel perforated arms. 80

4. A pressed-steel connection comprising a blank longitudinally slotted at its ends and rounded and perforated, and having the body portion pressed into inverted-U shape in cross-section, and provided with vertically-disposed perforated arms. 85

5. A pressed-steel connection comprising a blank slotted and perforated at its ends and pressed to provide a body portion the side walls of which are deflected toward each other, and to bring the perforated ends into vertical parallel relation. 90

In testimony whereof I affix my signature in the presence of two witnesses.

NEIL McINNES.
